SOUND RECORDING

Harold J. McCreary, Lombard, Ill., assignor to
 Radio Corporation of America, New York, N. Y.,
 a corporation of Delaware

Application June 9, 1932, Serial No. 616,285

6 Claims. (Cl. 101—426)

My invention relates in general to sound recording and has for its object new and improved methods and apparatus for the manufacture of sound records and for the production 5 of copies of such records.

A special object of the invention is the production of master sound records in the form of a metallic tape. Several new and improved methods of making such records are disclosed.

10 Another object of the invention is a new and improved process of producing copies of sound records on paper tape or other similar material by printing from a master sound record.

15 Another and related object is a new and improved process of producing copies of sound records by stencilling on paper tape from a master sound record.

20 A special object of the invention is the production of cheap and compact sound records for general use comprising reels of paper tape or similar material on which sound records are printed or stencilled.

25 A special object of the invention is an unusually compact sound record of the paper tape type, comprising an endless single surface tape having a continuous multi-track sound record on both sides.

30 A special feature of the invention is a reel for use with endless tape records of the single or double surface type. The improved reel provides for unwinding from the inside simultaneously with rewinding on the outside.

35 The foregoing and other objects and features of the invention will be pointed out more in detail hereinafter, reference being had to the accompanying drawings, in which:—

Fig. 1 is a diagrammatic view of apparatus for printing sound records on paper or other similar tape from a master tape sound record;

40 Fig. 2 shows in diagrammatic form an apparatus for producing copies of master tape sound records on paper or other tape by a stencilling process;

45 Figs. 3 and 4 are other views of portions of the apparatus shown in Fig. 2;

Fig. 5 is a diagrammatic view of an apparatus for producing master sound records of metal tape;

50 Figs. 6 to 11A, inclusive, show samples of metal tape master sound records and paper tape copies printed or stencilled therefrom;

55 Fig. 12 shows an endless single surface tape with a diagrammatic representation of a continuous sound record occupying both sides of the tape;

Fig. 13 shows a reel or spool for use with an endless single surface sound record tape, together with suitable rollers for drawing the tape from the reel and for rewinding it; while

Fig. 14 is a perspective view, partly in section, 5 of the reel shown in Fig. 13.

I will first describe a process of making a metallic tape master sound record which is suitable for use in the printing and stencilling processes illustrated in Figs. 1 and 2. The tape used 10 may vary as to size and material. However, a tape one inch wide and about .005 inch thick is all right for the purpose. The material may be steel, brass, or other metal. A zinc alloy known by the trade name "Eraydo" is also suitable. 15

In brief, the process is a photo-lithographic process very similar to what is in common used in printing plants throughout the country. After being first cleansed, the metal tape is coated all over with a sensitized film. This film is 20 soluble in water but portions thereof which are exposed to light are hardened and rendered insoluble in water or in the acid used in etching.

The treated film is next exposed in a sound recording apparatus. Such apparatus is well 25 known in the art and therefore need not be shown or described herein. Recording apparatus which makes a record of the variable width pattern may be used. Fig. 6 shows a section of sensitized metal tape after exposure. The shaded 30 area is the area which has not been exposed to light.

The exposed tape is then washed in clean water with the result that the film is washed away except where it has been fixed by the 35 action of light. In Fig. 6 the shaded area is washed clear of the film and also the entire rear side of the tape, none of which has been exposed. The rear side of the tape is then given a coating of acid resistant varnish. 40

The tape may now be run through an etching solution. This process is repeated a number of times until that portion of the tape which has not been exposed to light, the shaded area in Fig. 6, is entirely removed by action of the 45 etching solution. The varnish and the remainder of the film may now be cleaned off by the use of suitable solvents for these materials.

The finished tape sound record, or rather a section of it, is shown in Fig. 7. This is a varia- 50 ble width sound record.

A modification of the foregoing process will now be described in connection with Fig. 8. This process contemplates the use of a metal tape covered with a sensitized film the same as 55

in the foregoing. Instead of exposing it in an ordinary sound recording apparatus of the variable width type, however, the recording apparatus is modified by substituting a light slit 5 wide enough to cover the entire width of the tape. Close to the light slit and at right angles to it is stretched a thin wire which vibrates transversely of the light slit under the influence of a varying electric current corresponding to 10 the sounds to be recorded. This wire casts a shadow normally at about the centre of the tape and as the tape moves past the slit in the recording process the vibrating wire will produce a narrow unexposed area in the form of a wavy line. Fig. 8 represents a section of tape which 15 has been exposed in this way. The unshaded areas have been exposed to light, but the shaded wavy line down the center has not been exposed.

20 It will be appreciated now that by suitable treatment along the line of what has already been described the metal tape can be etched through and split down the center along the unexposed line, Fig. 8, so as to produce two 25 similar metal tape sound records. The upper half of the tape, Fig. 8, will become a record like Fig. 7, while the lower half will become a similar sound record, except that the indented portion is on the opposite edge.

30 Fig. 5 shows an apparatus for producing metal tape sound records by a method which is somewhat similar to the process described in connection with Fig. 8, but which dispenses with 35 photography.

35 In Fig. 5, 2 is a reel carrying the metal tape supply, while 14 and 15 are reels on which the finished tape sound records are coiled up. A vat or tank of liquid paraffin or similar substance is indicated by 8. Similar tanks containing acid and water, respectively, are indicated by 9 and 10. A pipe 7 provides a blast of cold air. The magnet 6 is connected in a circuit in which the sound currents to be recorded are flowing. For convenience the sound may first be recorded in 40 the usual way on a disc or film record. Any well known type of electrical pick up device may then be used and the magnet 6 is connected in the output circuit of the final amplifying stage. The magnet 6 has a pivoted armature 5 which 45 carries a stylus 4, in contact with the tape.

50 In setting up the apparatus the tape 3 is threaded under and over the rollers shown and through the dryer 11, but since the first portion to come through will not be separated into two halves it cannot at once be attached to the reels 14 and 15. The tape is therefore pulled through by hand for a short time in order to get the process started. As the tape passes through tank 8 it receives a coating of paraffin, which is 55 cooled and hardened by the air blast. The coated tape next passes under the stylus 4 which traces a line down the center, exposing the surface of the metal along the line. The tape then passes into the acid bath in tank 9. The acid dissolves the metal tape away where the surface is exposed thus separating it into two halves. From the acid bath the two halves of the tape pass through the water tank 10, where they are washed clean of acid, and through the 60 dryer 11, in which a current of hot air is maintained.

65 As soon as the tape begins to come through in two separate parts the end may be cut off and the two parts are then attached to the reels 14 and 15, respectively. The roller 16 over which

the split tape passes before being reeled up may be power driven so as to pull the tape through the apparatus at a constant speed. The sound apparatus may now be turned on. As magnet 6 becomes active the stylus 4 will produce a wavy line on the tape in accordance with the sound record, similar to the line shown in Fig. 8. As a result the tape will be split in two parts along a variable line, producing two sound record tapes which are reeled up on reels 14 and 15.

10 It will be understood that Fig. 5 is a diagrammatic illustration of the process described, and the parts may be suitably modified in practice. For instance, the length of the acid bath 9 must be sufficient to give the correct number 15 of immersions to sever the tape. The number required depends on the thickness of tape used, the solution used, and the speed of the tape through the apparatus. In any particular case the correct number should be found by trial 20 before the actual production of records begins. The acid bath may be constructed with the maximum number of rolls, and then one or more may be passed in order to limit the immersions to the requisite number.

25 Other parts of the apparatus may likewise be suitably modified. The reels 14 and 15 should of course be provided with suitable take up devices to maintain tension on the tape. Devices suitable for this purpose are known and hence 30 are not shown. However, I have designed a novel form of take up device which is shown in connection with Fig. 2 and which will shortly be described. This device may also be used with 35 reels 14 and 15.

Referring now to Fig. 1, which illustrates a process of printing sound records on paper or similar tape, the reference character 30 indicates a reel on which the master sound record is wound. This sound record may be metallic 40 tape record such as is shown in Fig. 7. In Fig. 1 the master sound record, partly unwound from reel 30, is indicated by 32. 41 is another reel to which the sound record tape 32 is transferred in the printing process. As shown, the tape 32 45 passes from reel 30 over an idler roller 31, and thence through the inking apparatus 33. From this point the tape passes through the printing rollers 34 and 35. A duplicate inking apparatus 43 and another pair of printing rollers 44 and 50 45 are shown, as the process contemplates the printing of a plurality of sound records simultaneously. From the last pair of printing rollers the tape 32 passes over the power driven roller 40, and thence to the take up reel 41. A motor 55 for driving roller 40 by means of a belt is indicated at 39. The printing rollers 35 and 45 are also preferably positively driven, and belts are shown for accomplishing this.

The reel 36 holds a supply of paper tape on 60 which the sound record is to be printed. This tape 38 passes over the printing roller 35 underneath the tape 32 and on to a take up reel 31. The reel 46 likewise holds a supply of paper tape. This tape 48 passes over the printing roller 45 65 and is wound up on reel 47. In the operation of the apparatus the roller 40 and the printing rollers 45 and 35 are driven at the proper speed and pull the metal tape 32 through the printing apparatus. Thus the tape 32 is gradually transferred from reel 30 to reel 41. Considering the left hand printing unit more in detail, the tape 32 first passes through the inking rollers in the inking apparatus 33, where it receives a coating of ink on the lower side. The tape next passes 70

through the printing rollers 34 and 35 where it comes in contact with the paper tape 38. The rollers press the two tapes together progressively, as tape 38 is also moving, being unwound from reel 36 and rewound on reel 37. Thus an impression of the tape 32 is printed on tape 38. As the tape 32 moves along it receives a new coating of ink at 43, which is transferred to the paper tape 48 where the two tapes are pressed into contact with each other by printing rollers 44 and 45.

The paper tapes 38 and 48 thus have printed on them exact impressions of the master sound record tape 32. They can be used in known photo-electric reproducers of standard type to reproduce audibly the original sounds. Fig. 9 shows a small section of a printed sound record made by the process just described. The black area is the ink impression of the master sound record.

Reference will now be made to Fig. 2 in order to describe the stencilling process of manufacturing sound records which is therein illustrated.

The reference character 50 indicates a reel which holds a master sound record tape 58 which may be similar to the one shown in Fig. 7. The tape 58 is shown partly transferred to the reel 57, on which it is gradually wound up. Intervening between the reels 50 and 57 is a large roller 53, over which the tape 58 is guided by smaller rollers 51, 52, 54 and 56. The roller 56 may be positively driven by any suitable means such as a motor 55, and thus serves also to drive the tape. It will be seen therefore that the tape 58 passes off the reel 50 and over the roller 51, from which point it passes successively under roller 52, over the large roller 53, and under the roller 54. From roller 54 the tape 58 passes over the driven roller 56 and then on to the reel 57. The rollers 52 and 54 have the special function of holding the tape in contact with the roller 53 for a considerable angular distance around its periphery. The purpose of this is to maintain close contact with the paper tape 61 during the stencilling operation and to provide for enough friction to effectively drive roller 53. Of course a separate positive drive for roller 53 can be provided but this is not generally necessary.

As stated hereinbefore the metal tape 58 is wound up on reel 57 as fast as it is pulled off from reel 50. This is accomplished by a take up apparatus which may now be described briefly; reference being had to Figs. 2 and 4. The member 71 may conveniently be pivoted on the shaft 70 which carries the driving roller 56, and at its lower forked end it carries a small roller 77 which rests against the wound up tape on reel 57. Member 71 also has attached to it a bracket member 72 which passes around one edge of reel 57 and at its end carries a short shaft. On this shaft there is rotatably mounted a driving unit comprising a pulley 74 and a friction wheel 75, the latter of which bears against the side of reel 57 as shown. Outside of the driving roller 56 the shaft 70 carries a small pulley 73. The pulley 73 is connected with the pulley 74 by a belt 76. With the apparatus in operation, the tape 58 is fed through to reel 57 by the driving roller 56. At the same time, the pulley 73 is rotating and drives the friction wheel 75 by means of belt 76 and pulley 74. The relative size of pulleys 73 and 74 should be such that the reel 57 tries to wind up the tape 58 a trifle faster than it is fed forward by driving roller 56, thus maintaining the tape taut. The friction

wheel 75 has a light contact with the reel 57 and slips a little. As the tape 58 is reeled up the diameter of the wound up body of tape on reel 57 increases which makes it necessary to gradually slow down the speed of reel 57. This is taken care of by the arrangement including roller 71, resting on the wound up tape. As the tape accumulates on reel 57, roller 71 moves the end of arm 71 outward and causes the friction wheel 75 to move toward the outer edge of reel 57, thus slowing down the speed of reel.

The take up device just described is suitable for use in connection with other reels shown in the drawings, but has been shown at only the one point in order to avoid unnecessary complication. For instance, a take up reel of this type could be used in place of reel 41, Fig. 1, or in place of the reels on which the paper tape records are wound up, such as reel 37.

The paper tape on which the stencilled sound record is made is carried by reel 60. This tape, indicated at 61, passes off reel 60 and over the large roller 53. At the point where the tape 61 goes over roller 53 it lies underneath the master record tape 58. From roller 53, the tape 61 passes through a dryer 62, over a guiding roller 63, and thence on to the take up reel 64.

The stencilling apparatus is shown in Fig. 2 just above the roller 53, and is also shown in section in Fig. 3. The apparatus is enclosed in a container 80, at the bottom of which is a supply of stencilling liquid as indicated in Fig. 3. The stencilling is performed by means of a fine spray of liquid produced by an aspirator which includes the air pipe 81 and the tube 82. That portion of the container 80 which extends over the roller 53 has a narrow slit therein, toward which the spray is directed.

The process will doubtless be sufficiently understood from the description of the apparatus employed, but may nevertheless be described briefly. As the master record tape 58 is drawn through the apparatus it rotates the roller 53 which drives the paper tape 61. The two tapes are in close contact as they pass over roller 53. As the tapes pass under the slit in container 80 they receive the spray of stencilling liquids or that portion of it which goes through the slit, and thereby a substantial part of the surface of the paper tape which is not covered up by the master tape is given a coating of the stencilling liquid. The width of the slit is preferably such that the spray does not extend quite to the edge of the tape 61, so as not to get any on the roller 53.

The two tapes separate underneath roller 54 and the paper tape 61 proceeds down through the dryer 62, after which it is wound up on reel 64. If desired the master tape 58 may be passed through a suitable arrangement for washing off or otherwise removing the liquid from its surface before it is wound up. A section of the complete stencilled paper tape sound record is shown in Fig. 10. In Fig. 10 the black area is that portion of the tape which is coated with the stencilling liquid while the upper light area is the portion which was covered up by the master tape. The master tape intercepts a variable amount of the spray and thus causes the stencilled band to vary in width in accordance with the sound record.

The amount of conversation, music or other sounds which can be recorded on a given length of metal tape depends on the speed at which the tape moves during the recording process.

In order to record the maximum amount the tape is therefore moved as slow as possible consistent with other factors. If the recording process is carried out at a fairly high speed the successive variations in width which occur in the resulting tape record will be relatively far apart and will be more or less rounded off, which makes a tape record which is not easily damaged. In Fig. 7, for instance, it will be seen that the serrations on the lower edge of the tape are substantial and not especially liable to be broken off. In making a sound record tape like Fig. 7, the recording process is carried out at a fairly high speed. It would be possible to slow the speed of recording down somewhat, but as the speed is reduced the serrations would come closer together, so that before long a point would be reached beyond which no further reduction in speed could take place without producing a record with serrations so fine that they would be easily damaged in handling the tape during the printing or stencilling process.

In order to increase the length of the sound recorded which can be carried by a metal tape a somewhat different form of tape may be used, as will be explained in connection with Figs. 11 and 11A.

The metal tape may be bi-metallic, that is, composed of layers of two different metals. The process is facilitated if one metal, the one which forms the rear layer, is less susceptible to the etching acid than the other metal. The process of recording sound on such a tape is similar to the photographic process described, except that the tape may be moved at a much slower speed during exposure to light. After exposure, the etching process is carried far enough so that the upper layer of metal is removed where it has not been exposed, the process being stopped as soon as the rear layer of less susceptible metal is reached. The rear layer, being left intact, forms a backing for the irregular upper layer in which the sound record has been etched.

Fig. 11 shows a section of a completed bi-metallic tape sound record made according to the foregoing, and Fig. 12 is an end view. In Fig. 11 the unshaded area is the upper layer of metal in which the sound record is formed, while the shaded area is that portion of the rear layer of metal from which the upper layer has been removed. Both layers can be seen also in Fig. 11A. It will be observed that the serrations are much closer together than in Fig. 7, but this is not particularly objectionable from a mechanical standpoint, as it would be in a tape record like Fig. 7, because the fine points are protected by the rear layer of metal.

It will be clear that a record of this type can be made from a plain single layer metal tape, which, however, should be thick enough so that the etching process can be stopped after the metal has been removed to a depth of about .005 inch, leaving a sufficient amount of metal to give the required support and protection. The use of a bimetallic tape merely renders the manufacture of the record somewhat easier.

Records of the type shown in Fig. 11 are of course not adapted to the stencilling process shown in Fig. 2. They are intended for use in the printing process which has been described in connection with Fig. 1.

Referring now to Fig. 12, this drawing shows a diagrammatic plan view of an endless single surface tape of paper or other material on which a sound record may be printed or stencilled by

one of the processes hereinbefore described, or by any other suitable process. In view of the small scale of the drawing no attempt has been made to show an actual sound record, but the record is indicated by the line 92. It may be stated at the outset that the object in view in designing this particular form of tape sound record is to produce a tape bearing a continuous sound record occupying parallel paths on both sides of the tape, thus providing for recording 10 the maximum amount of sound on a given amount of tape.

The tape will be many yards in length in practice, and will be coiled up in a roll, as will be explained subsequently. The short tape shown 15 in Fig. 12 can conveniently be made use of in explaining the principle involved. This tape has been shown flattened out or bent over at equally spaced points 85, 86 and 87, forming three equal sections 88, 89, and 90. Thus the path of the 20 record represented by line 92 can readily be traced.

The record 92 may be assumed to start at point 91 on the upper surface of section 88. From point 91, it may be traced downward in 25 the direction of the arrow and around bend 86, along the under side of section 89, as shown by the dotted line, around bend 87, upper surface of section 90, around bend 85 on the inside, lower surface of section 88, around bend 86 (inside), 30 upper surface of section 89, around bend 87 (inside), lower surface of section 90, and around the upper bend 85 to the upper surface of section 88, where it passes the starting point 91. It will be seen from the foregoing that the line 92 35 passes around the tape twice lengthwise before returning to the vicinity of point 91, where it started. In thus traversing the length of tape the line appeared on both sides of each section thereof.

It will be understood that the record represented by line 92 works gradually to the right, considering section 88, so that when it finally appears near point 91 after making a double circuit of the tape, it will be displaced sufficiently 45 so that it can continue on around without being superimposed on itself. The amount of displacement required depends on the width of tape required for one sound track. Satisfactory records can be made of the variable width type which 50 are somewhat less than $\frac{1}{4}$ of an inch in width. A sound track of this width can pass a considerable number of times around the tape before it is filled up. If the tape is two inches wide, there may be eight parallel sound tracks on each side 55 of the tape at any particular point. This means that the continuous sound track will pass sixteen times around the tape. It will be appreciated that a very large amount of speech or music can be recorded on a moderate length of 60 tape.

A suitable reel for handling an endless double surface tape such as has just been described is shown in Figs. 13 and 14. These drawings are more or less in diagrammatic form, although they show clearly the construction of the reel and the principle involved in its operation.

The various parts of the reel are supported on a base member 101, which may be of any suitable form. On the base 101 is mounted a disc 71 102, which is pivoted at 103 so as to rotate freely. On opposite sides of the disc 102 there are two upright members 104 and 105 which are firmly attached to the base 101. These members can be seen clearly in the perspective drawing Fig. 71

14. The member 105 does not appear in Fig. 13, having been omitted along with part of member 106 in order to avoid obscuring other parts. The member 106 extends across between the upper 5 ends of member 104 and 105 to which it is secured. On the lower side of cross member 106 is secured a fixed disc or plate 107.

The disc 107 carries on the lower side thereof a circular row of rollers 110. There may be 10 twelve or more of these rollers equally spaced around the circumference of a circle. Each roller may be mounted on a stud which is screw threaded into the disc 107 as indicated in the case of the left hand roller 110 in Fig. 14. These 15 rollers extend downward toward the rotatable disc 102 but do not quite reach it, sufficient space being allowed so that the rotation of disc 102 will not be interfered with.

Inside the circle described by the rollers 110 is 20 mounted a member 112. This member 112 is a round polished rod and is firmly secured to the disc 107 at its upper end. It lies in a plane substantially parallel to member 106 and the end points downward at an angle of forty-five degrees. As in the case with the rollers 110, the 25 lower end of member 112 should clear the disc 102.

As will be seen clearly from the drawings the 30 main portion of the tape 115 is formed in a roll and is supported on the rotatable disc 102. The inside layer of tape fits loosely around the rollers 110. At a point just in front of the left hand roller 110, see Fig. 14, the tape leaves the 35 roll and extends between this roller and the next one to it in a counter clockwise direction, passing toward the center. The tape then passes under and around the member 112 and extends upward through a slot 119 in the disc 107 and the cross member 106.

40 Certain rollers are shown in the drawings for the purpose of drawing the tape off the reel and for guiding it back on. Referring particularly to Fig. 13, the rollers 116 and 117 are mounted above the reel as shown. The roller 116, or roller 45 111, may be driven from some suitable source of power. The tape 115 passes over roller 116, then over a roller 118, and thence back on to the reel. Roller 117 preferably is pressed against roller 116 by spring tension or other means in 50 order to avoid any possibility of the tape slipping on roller 116.

In the operation of the reel, the rotation of 55 roller 116 moves the tape 115 in the direction shown by the arrow. As can be seen more clearly from Fig. 14, the tape is drawn off from the center of the roll, around roller 110, around the rod 112, where it changes its direction, and upward through the slit 119 toward roller 116. This operation causes a rotation of the main 60 body of the roll which is supported on the disc 102. The roll and disc therefore rotate, in a counter clockwise direction. The rotation of the main roll winds up the tape as it leaves roller 118. This produces some tension in the 65 tape which causes the main body of the roll to gradually collapse by slipping of the layers. The construction is such as to eliminate friction as much as possible and the tape is pulled off easily. There is no tendency to bind around the 70 rollers 110 or between the layers of the main body of tape because the tape is being drawn off from the inside of the roll, which tends to constantly increase the diameter of the inner layer. This tendency is just overcome by the tension produced by winding up the tape on the 75

outside, which causes the layers to slip on one another and maintain the size of the roll constant.

In order to permit of readily changing rolls the 5 cross member 106 is preferably removably secured to the upright members 104 and 105 so that the assembly comprising cross member 106, disc 107, and rollers 110 can be lifted off. A slot 120, Fig. 13, is also cut in disc 107, connecting with slot 119, so as to permit the tape to be 10 inserted or removed.

A reel of the type just described can be used in manufacturing printed or stencilled paper tape records of the endless single surface type such as is shown in Fig. 12. The process illustrated in Fig. 1; or the stencilling process shown in Fig. 2 may be used. In Fig. 1, for instance, the tape 38 and reels 36 and 37 may be replaced by tape 115 and the reel shown in Fig. 13, together with rollers 116, 117, and 118, that section of the tape 115 which extends between rollers 116 and 118 being passed over roller 35. Or rollers 116 and 117 could be omitted, being replaced by roller 35. It will be understood that in an assembly of this kind the reel and associated rollers for guiding the tape must be mounted on a base or platform which can be traversed in a direction perpendicular to the master tape, thereby providing for printing a continuous record on the tape in parallel paths. 30 Apparatus for providing a slow movement such as is required in this case is well known in this art and need not be described herein.

Having described my invention, what I consider to be new and desire to have protected by 35 Letters Patent will be pointed out in the appended claims:

1. The process of copying a master tape sound record of the variable width type, on tape of 40 paper or similar material which consists in producing a spray of stencilling liquid, in passing the paper tape through the spray, in simultaneously passing the master tape through the spray in contact with the paper tape on the side thereof against which the spray is directed, and 45 in restricting the cross section of said spray to a point adjacent said tapes.

2. In combination, a sound record comprising 50 a master tape of variable width, means for bringing successive portions of one side of said tape in contact with corresponding portions of a second tape, with their flat sides together, means for directing a spray of coating material against a portion of the master tape and an exposed portion of said second tape while the tapes are in 55 contact, and means for blocking the spray from the remaining portion of said master tape and from a part of the exposed portion of said second tape.

3. In combination, a master tape having a 60 sound record formed thereon, means for producing a spray of stencilling liquid, means for progressively passing successive portions of a second tape under said spray, means for simultaneously intercepting portions of said spray 65 with successive portions of said master tape, and means for intercepting all except a predetermined limited portion of said spray before it reaches said master tape.

4. The process of making a sound record on 70 a paper tape from a master tape sound record of the variable width type, which consists in moving said tapes simultaneously and in superimposed relation past a fixed point, in pressing said tapes together as they pass said point, in 75

directing a spray of stencilling liquid toward the tapes where they are pressed together, in intercepting the spray on one side at a point above the master tape, and in intercepting the spray 5 on the other side at a point above continuously exposed portions of the paper tape, whereby a record is produced on the paper tape having a straight edge on one side and an irregular edge on the other side as determined by the width 10 of the master tape.

5. The process of making a sound record on a paper tape from a master tape of the variable width type, which consists in moving said tapes simultaneously with the master tape superimposed on the paper tape and in contact therewith, in adjusting the moving tapes laterally so that a portion of the paper tape is exposed along the variable edge of the master tape where the 15 tapes are in contact, in directing a spray of stencilling liquid toward the tapes from the master tape side, and in confining said spray 20 where it approaches the master tape to a width

which leaves a part of the master tape and a part of the paper tape uncoated while depositing along the overlapping variable edge of the master tape a coating which reproduces on the paper tape all the width variations in the master 5 tape.

6. In combination, a sound record comprising a master tape varying in width and equal in length to a section of paper tape on which the record is to be reproduced, means for moving 10 said tapes uniformly and uninterruptedly and at the same rate, means for forming a semi-circular loop in the moving tapes, means for maintaining said tapes out of contact except at the said loop and for pressing them together at 15 that point, and means including said master tape for applying to said paper tape as the master tape is pressed against it a continuous coating having variations in width corresponding to the variations in width of the master 20 tape.

HAROLD J. McCREARY.
